UNITED STATES PATENT OFFICE

96,281

DESIGN FOR A BANNER OR SIMILAR ARTICLE

Joseph Schrembs, Cleveland, Ohio

Application May 31, 1935, Serial No. 57,077

Term of patent 3½ years

To whom it may concern:

Be it known that I, Joseph Schrembs, a citizen of the United States, residing at Cleveland, in the county of Cuyahoga and State of Ohio, have invented a new, original, and ornamental Design for a Banner or Similar Article, of which the following is a specification, reference being had to the accompanying drawing, forming a part thereof.

The drawing is a view of a banner to which the design is applied, the characteristic feature of the design being a shield which bears the representation of a religious article, such as a monstrance.

I claim:—

The ornamental design for a banner or similar article, as shown and described.

JOSEPH SCHREMBS.
